(57) **CLAIM**

We claim the ornamental design for a dock for a portable electronic device, as shown and described.

DESCRIPTION

FIG. 1 is a perspective view of a dock for a portable electronic device embodying the invention.

FIG. 2 is a first side view of the dock of FIG. 1.

FIG. 3 is a second side view of the dock of FIG. 1.

FIG. 4 is a front view of the dock of FIG. 1.

FIG. 5 is a rear view of the dock of FIG. 1.

FIG. 6 is a top view of the dock of FIG. 1; and,

FIG. 7 is a bottom view of the dock of FIG. 1.

Portions of the dock shown in broken lines are for illustrative purposes only and form no part of the claimed design.

1 Claim, 7 Drawing Sheets
